[57] **CLAIM**

The ornamental design for a tool pouch for bucket, as shown and described.

DESCRIPTION

FIG. 1 is a perspective view of a tool pouch for bucket showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken line showing of a bucket and handle is for illustrative purposes only and forms no part of the claimed design.

FIG. 1

FIG. 2FIG. 3FIG. 4FIG. 5FIG. 6FIG. 7
